UNITED STATES PATENT OFFICE.

JOHN R. THOMAS, OF WILKES-BARRE, PENNSYLVANIA.

ABRASIVE TOOL.

1,012,479.

Specification of Letters Patent. Patented Dec. 19, 1911.

Application filed September 28, 1911. Serial No. 651,417.

To all whom it may concern:

Be it known that I, JOHN R. THOMAS, a citizen of the United States, residing at Wilkes-Barre, in the county of Luzerne and State of Pennsylvania, have invented a new and useful Improvement in Abrasive Tools, of which the following is a specification.

My invention relates to blocks or clamps for holding abrasive fabric, such as emery cloth, sandpaper and the like, the blocks being of such size and formation as to form a hand tool for smoothing and polishing operations.

Referring to the drawings, Figure 1 is a perspective view of my improved blocks; Fig. 2 is an end elevation of the same; Fig. 3 is a plan view of the lower block, and Fig. 4 is a sectional front elevation.

As shown, the tool is made in two parts, and its rectangular dimensions are such that it is adapted to seat and clamp a quarter-section of standard size sandpaper. The lower block 10 is provided with a cork layer 12 to form a resilient backing for the paper. The top surface of the block is hollowed out longitudinally and is formed preferably of two reentrant angles 13, 13 with an intermediate flat, as shown in Fig. 2. A transverse plate 15 provided with notch 16 is located centrally upon the upper surface of the block, the angular parts 13, 13 being cut away to bed the plate 15 firmly upon the intermediate flat. A cavity 17 is located in the block in registration with the slot 16, as shown in Fig. 3.

The upper block 11 has its lower surface shaped to correspond with or match the lower block, and is fitted with a partly countersunk thumb-screw 14. The thumb-screw is provided with a left-hand thread 19 which engages a nut plate 22 fastened to the block 11. Below the threaded portion of the thumb-screw is a small shank 20 terminating in a head 21. The abrasive fabric 18, as shown in Fig. 2 is clamped between the blocks 10 and 11.

To clamp the blocks together, all that is necessary is to place the two together so that the head 21 of block 11 is in the cavity 17 of block 10. The blocks are then slid longitudinally upon each other until the shank 20 enters the slot 16. A quarter turn of the thumb-screw to the right is then sufficient to clamp the blocks rigidly together with the fabric gripped between them.

It will be noticed that the arrangement

of parts is such that the entire rectangular bottom of the lower block may be completely covered with the sandpaper or emery cloth and that there are no projections on either the sides or the top of the blocks which extend beyond the fabric when it is clamped in position. This feature is of great value in allowing the block to be used in corners and it enables the tool to be used effectively on shouldered work and in many other cases where a block with projecting parts could not be used.

It is obvious that many changes may be made without departing from the spirit of my invention, as the substitution of felt or rubber for the cork layer, and minor modifications of the clamping device, so that I do not restrict myself to the particular arrangements of parts as shown and described.

I claim:

1. In combination, a pair of matched blocks for clamping abrasive fabric, one of said blocks having its lower surface faced with resilient material to serve as a backing for the clamped fabric, and its upper surface of an approximately concave form, a locking plate mounted on the block, and the second block, having one surface of approximately convex form to match the upper surface of the first block and a screw bolt passing through said second block and adapted to engage the said locking plate to clamp the two blocks together, substantially as described.

2. In combination, a pair of matched blocks for clamping abrasive fabric, one of said blocks being provided with the plate 22 having a threaded aperture, a bolt having a threaded portion 19 engaging the plate 22, a shank 20, and a head 21, the said head 21 being of a smaller diameter than the internal diameter of said aperture so that said bolt and plate may be separated, and means carried by the second block 100 adapted to coöperate with said bolt to lock the two blocks together, substantially as shown and described.

3. In combination, a pair of matched blocks for clamping abrasive fabric, the block 11, being provided with a plate 22, a thumb-screw 14 having an intermediate threaded portion 19 engaging said plate, and having a reduced shank 20, and a head 21, the head being of lesser diameter than the threaded portion 19 measured at the bottom of the thread, the said thread being

left-handed, and the block 10 carrying the notched plate 15 adapted to coöperate with the thumb-screw 14, substantially as described.

5. 4. In combination, a pair of matched blocks for clamping abrasive fabric, one of said blocks having reëntrant angles 13, 13, the second block having complementary angles thereto, one of said blocks having a 10 notched plate, the other block having a bolt

adapted to enter the said notch and engage the plate, the arrangement being such that the blocks may be completely separated from each other, substantially as shown and described.

JOHN R. THOMAS.
